UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

FLUID COMPRESSOR.

Application filed February 23, 1927. Serial No. 170,410.

This invention relates to fluid compressors and more particularly to improved driving means for such compressors.

An object of this invention is to provide a fluid compressor having its driving motor arranged in an improved and simplified manner relative to the compressor crank shaft. Another object of this invention is to provide an improved compressor of the synchronous motor driven type wherein the rotor of the driving motor is secured directly to the compressor crank shaft while the stator is mounted directly on the compressor base. Still another object is to provide an improved compressor unit which is of exceedingly compact construction, the floor space required for setting up the compressor being reduced to a minimum. Another object is to provide an improved compressor wherein a common base is provided for supporting both the compressor and the driving motor. These and other objects and advantages of this invention will, however, subsequently more fully appear.

In the accompanying drawings there is shown for purposes of illustration one form and a modification thereof which the invention may assume in practice.

In these drawings,—

Fig. 1 is a side elevational view of the improved fluid compressor.

Fig. 2 is an end elevational view of the compressor shown in Fig. 1.

Fig. 3 is an enlarged transverse vertical sectional view taken on line 3—3 of Fig. 1, parts being shown in elevation to simplify illustration.

Fig. 4 is a detail sectional view illustrating the adjusting means for the motor casing.

Fig. 5 is a detail view illustrating a slightly modified form of construction.

In this illustrative construction there is shown a fluid compressor of the so-called angle compound type having a frame 1 on which are disposed at right angles with respect to each other compressor cylinders 2 and 3. The horizontally disposed cylinder 2 is the low pressure cylinder from which the compressed fluid is discharged through an inter-cooler 4 to the vertical high pressure cylinder 3. As is usual in compressors of the type disclosed, the cylinders 2 and 3 contain reciprocable pistons (not shown) driven from a common crank shaft 5. The crank shaft 5 is horizontally disposed and extends trans-

ported in suitable bearings 6 suitably carried by the frame 1. As clearly shown in Fig. 3 the crank shaft 5 projects laterally through the side of the frame 1 a substantial distance as at 7. The compressor is mounted on and rigidly secured to a base frame 8 having a laterally projecting portion 9. The portion 9 of the base frame is recessed as at 10 for a purpose to be later described.

In the improved construction the driving motor for the compressor is herein preferably of the synchronous type having its stator 11 mounted in an improved manner on the laterally projecting portion 9 of the base frame 8. The rotor 12 of the driving motor is mounted directly on and rigidly fixed to the laterally projecting portion 7 of the compressor crank shaft. Improved means are provided for alining the stator 11 of the motor relative to the rotor 12; and this means specifically comprises bearing plates 13 suitably fixed to the base frame 8 and having threadedly connected thereto set screws 14 and 15 at each side thereof. The set screws 14 when adjusted are adapted to vary the lateral position of the stator 11 with respect to the rotor 12, while the set screws 15 are adapted to adjust the stator vertically. If desired, however, the set screws 15 may be omitted and shims inserted between the frame 13 and the stator 11 to adjust the vertical position of the latter. The side members or feet of the motor engage bearing plates or pads 16 supported on the plates 13. Referring to Fig. 3 it will be noted that the wires 17 leading to the motor windings project downwardly from beneath the motor within the recess 10 formed in the base frame.

In the modification shown on Fig. 5 the laterally projecting portion 9 of the base frame 8 has been extended as at 18 and mounted on this base frame portion is an outboard bearing 19 in which the compressor crank shaft is rotatively mounted. However, in the smaller types of compressors such as those shown in Figs. 1 to 3, the outboard bearing 19 is unnecessary, the rotor of the motor being supported entirely by the compressor crank shaft.

As a result of this invention an improved fluid compressor is provided which is exceedingly compact in construction, the driving motor being mounted directly on the base of the compressor and having its rotor supported entirely by the compressor crank shaft. It

will further be noted that by arranging the motor in this manner it is possible to support the motor in close proximity with the compressor frame. These and other advantages 5 of this invention will be clearly apparent to those skilled in this art.

While I have in this application specifically described two forms which the invention may assume in practice, it will be understood that 10 these forms of the same are shown for purposes of illustration and that the invention may be modified and embodied in various other forms without departing from its spirit or the scope of the appended claims.

15 What I claim as new and desire to secure by Letters Patent is:

1. In combination, a supporting base, pumping mechanism supported thereby including a horizontal crank shaft, and a driving motor mounted on said base and having its rotor fixed directly to said crank shaft and its casing secured to said base and surrounding said rotor out of contact with said crank shaft.

25 2. In combination, a supporting base, pumping mechanism supported thereby including a horizontal crank shaft and bearings for said crank shaft, and a driving motor for said pumping mechanism, said motor comprising a rotor fixed directly to said crank shaft and a casing adjustably secured to said base, the bearings for said crank shaft being supported by said base independently of said motor casing.

30 3. In combination, a supporting base, pumping mechanism supported thereby including a horizontal crank shaft and bearings for said crank shaft, a driving motor for said pumping mechanism, said motor

comprising a rotor fixed directly to said 40 crank shaft and a casing carried by said base, and means for adjusting said motor casing laterally relative to said base, said bearings for said crank shaft being supported by said base independently of said motor casing. 45

4. In combination, a supporting base, pumping mechanism supported thereby including a horizontal crank shaft and bearings for said crank shaft, a driving motor for said pumping mechanism, said motor 50 comprising a rotor fixed directly to said crank shaft and a casing carried by said base, and means for adjusting said motor casing laterally and vertically relative to said base, said bearings for said crank shaft being sup- 55 ported by said base independently of said motor casing.

5. In combination, a supporting base, pumping mechanism supported thereby including a frame and a horizontal crank shaft, 60 and a driving motor for said pumping mechanism, said motor comprising a rotor fixed directly to said crank shaft and a casing adjustably secured to said base, said crank shaft being supported solely by said frame. 65

6. In combination, a supporting base, pumping mechanism supported thereby including a horizontal crank shaft and bearings for said crank shaft, and a synchronous driving motor for said pumping mechanism, 70 said motor comprising a rotor fixed directly to and supported entirely by said crank shaft and a stator adjustably secured to said base, the bearings for said crank shaft being sup- 75 ported by said base independently of said stator.

In testimony whereof I affix my signature.
HALBERT B. HALVORSEN.
